UNITED STATES PATENT OFFICE.

FRANK PAVLIK, JR., OF WESTMINSTER, COLORADO.

DRY CLOSET.

1,248,901.

Specification of Letters Patent.

Patented Dec. 4, 1917.

Application filed July 31, 1917. Serial No. 183,677.

To all whom it may concern:

Be it known that I, FRANK PAVLIK, Jr., a citizen of the United States, residing at Westminster, in the county of Adams and State of Colorado, have invented certain new and useful Improvements in Dry Closets; and I do hereby declare the following to be a full, clear, and exact description of the invention, such as will enable others skilled in the art to which it appertains to make and use the same.

This invention relates to improvements in dry closets of a ventilated sanitary indoor chemical type.

Its advantages and novelty partly reside in the structural formation and arrangement of the container itself, but a particularly desirable feature is to provide for a satisfactory, readily detachable and attachable adjustable connection between the container proper and its vent pipe leading outdoors.

The unsanitary, unsightly, and other inconvenient and objectionable features of out-door privies being well understood, the chemical type of indoor closet is primarily designed for use on the farm, homestead, or other outlying localities, where the facility of city sewerage is not available, and hence the usual water flushing closets are not feasible for installation. Their object, therefore, is to provide a dry closet for use indoors, which is effectively odorless and substantially sanitary, rendering the same largely unobjectionable in these highly essential requirements.

These ends are broadly accomplished by the employment of a portable container, charged with a liquid mixture impregnated with a suitable chemical of a non-combustible and substantially non-poisonous nature, but which has sufficient strength to function as a germicidal decomposer and deodorizer, to throw down or destroy the acids, stench and poisonous gases arising from the fecal and urine contents.

While certain advantages of this type of closet are manifest, still many of them, as heretofore constructed, have proven more or less objectionable and unsatisfactory in practical use, and my main object is to improve conditions generally, providing at the

same time, and at low cost of manufacture, a durable and effective portable closet, adapted to be coupled up with a vent pipe, through an improved form of detachable connection, the whole equipment being designed for ready installation, by the purchasers themselves, with comparatively little trouble and expense—an end especially desirable in sparsely settled localities.

Having thus generally stated the object of the invention, I will now describe more fully the improved construction and combined arrangement of parts, the special features of novelty being more succinctly set forth in the appended claims; and in order to clearly understand same, reference is had to the accompanying drawings, forming a part of this application, in which drawings like parts are designated by the same reference numerals throughout the several views, of which

Figure 1, is a vertical sectional view, taken on a plane through the closet proper and its coupled connections with its vent pipe;

Fig. 2, is a similar enlarged view of the details of the coupled connections;

Fig. 3, is an enlarged sectional view, illustrating the facile means of making an air tight joinder between the upper shell and lower container, where a two part receptacle is employed, as shown in Fig. 1;

Fig. 4, is a detail sectional view on the line 4—4 of Fig. 2; and

Fig. 5, is an elevational view, partly broken away, of a slightly modified arrangement, employing a unitary form of container, instead of the two-part construction of Fig. 1.

1 designates a vent pipe leading to the atmosphere in any suitable manner, but it may preferably terminate above the ridge pole of the building.

To the lower end of this vent pipe 1 is telescoped the hollow end 3 of a support 2, providing an upper vent chamber, fixedly secured in place, as to the wall or floor of a room. In practice this may simply be a tubular standard or pipe, having a flanged base 3, screwed or bolted to the floor, as shown.

The upper vent chamber of this tubular

standard 2 has a lateral upturned elbow 4 associated, through interposed means, with a specially formed hollow element of the container receptacle, hereinafter described, 5 to provide a readily attachable and detachable air tight connection therebetween.

Broadly, this air-tight readily attachable and detachable coupling might be made through more or less rigid connections, employing 10 certain features of my improvements. However, I have shown and will now describe in detail a connection provided with an equalizing or self adjusting element for insuring an air tight joinder.

15 To this end, the up-turned portion of the elbow 4 may be threaded to receive a threaded member 5, functioning as a guiding sleeve or receiving part for the lower end of a hollow open-ended retractile element 6, between 20 the bottom edge of which and the upper edge of the elbow 4 is interposed a spring 7, preferably of coiled formation.

The lower end of the element 6 may be suitably flanged, as at 8, to provide a bearing 25 surface with the encompassing sleeve 5, and otherwise functioning as an abutting shoulder for the spring 7 and a limiting stop against the upward displacement of the retractile element. When the parts 5 and 30 6 are assembled, the upper end of the former may be turned inwardly to provide an internal flange 9 to coöperate, as a limiting means, with the flange 8, but it is obvious that these details may be varied.

35 The upper end of the element 6 is suitably formed or provided to seat a suitable gasket 10, for establishing an air sealing contact with the hollow projecting element of the container receptacle, before referred to and 40 which will presently be described.

In the illustration, the upper end of the element 6 is simply shown as having an external flange, bent inwardly upon itself and thence slightly upwardly, to provide a recessed seat 11 for the gasket 10, which latter 45 may be of rubber, leather, or other suitable form of cushioning elastic material.

The removably connected portable container itself is indicated at 12 in Figs. 1 and 50 3, and at 13 in Fig. 5. It may be provided with the usual bail or handle 14.

Whether the closet be built up sectionally or of unitary formation for its full height, in both cases the upper portion of the peripheral wall is apertured and provided 55 with a communicating hollow lateral extension or projection 15, which may be of substantial oval contour as shown, if desired, the outer end being closed as at 16, and its 60 underneath wall depressed inwardly to form a beveled-faced seating recess 17, the depressed underneath wall being suitably apertured, indicated by a single large orifice or opening 18, which is adapted to register

with the tubular retractile element 6, when 65 the fixtures are assembled in connected relation as referred to later.

In the two-part receptacle, illustrated in Figs. 1 and 3, the top section is in the form of a surmounting shell 19, the upper end of 70 which is bent inwardly as a downwardly inclined marginal rim 20, providing the central enlarged opening 21.

The lower end of the shell is curved inwardly and downwardly, as at 22, and is 75 also open as indicated at 23.

On the outside of the lower portion of the upper shell 19 is suitably secured a skirted or outwardly flaring encircling member 24, which with the inwardly curving lower portion of the shell provides an annular diverging or crotched seating recess, obviously adapted to readily adjust itself on top of the lower container proper, an air tight joinder or seal being made by the insertion of a suitable cushioning gasket 25 inserted well up into the apex of the recess. This arrangement will also prevent the soil and urine from being splashed up and slopping over the container—a very objectionable feature 90 in point of cleanliness and sanitation.

26 designates the usual apertured toilet seat, having the lid 27 hinged thereto at 28, and the seat, in turn, hinged at 29 to the hollow extension 15, the arrangement providing 95 for the use of the closet both as a covered stool and urinal.

These analogous parts are designated by similar numerals in Fig. 5, but in this latter figure, the marginal rim 20 is omitted, the 100 top of the container 13 being formed like the lower container 12 of Fig. 1, to permit of the contents being easily dumped and the container thoroughly cleaned and flushed out, when removed for emptying.

As in the non-ventilated form of chemical closets, I also employ a suitable chemical mixed in liquid form, but with the additional ventilating features, of course, the noxious odors and gases, not entirely killed 110 by chemical action, are conducted away, as indicated by the arrows, through the connections to the vent pipe 1, and from thence are discharged exteriorly of the building.

When the closet is dissociated from its 115 vent connections, the tubular element 6 will be forced upwardly under pressure of the spring 7, but it cannot be entirely displaced and lost, owing to the limiting stop elements 8 and 9.

But when the container receptacle is in position and the upper shell section of Fig. 1 is being replaced thereon, the crotched recess at its lower end will readily guide itself into air-tight connection with the top of the 125 container below, especially made air-tight through the interposition of the gasket 25. At the same time the bevel-faced recess or

depression 17 will find and guide itself into sealed relation with the upper open end of the tubular retractile element 6, through its seated gasket 10, which retractile element 5 will be accordingly forced downwardly; but the spring tensional force upwardly thereon will equalizingly balance or cause the retractile element to adjustably accommodate itself to the opposing forces, and with the 10 gasket 10 will always insure an intimate non-leak connection, although at the same time providing a readily separable joinder or coupling between the coöperating parts.

The only differences between the slightly 15 modified disclosure in Fig. 5 and that of Fig. 1 are in the construction of the container itself as a unitary receptacle, and therefore require no further specific description as to operation.

20 The connections as set forth have been found to ordinarily suffice for venting purposes, but if desired, it will be obvious that any of the well known means of forced draft sometimes used in ventilation systems, 25 such as a current of generated heated air or the suctional or propulsive force created by a fan or blower, may be employed.

While I have thus fully described a practical and preferred embodiment of the invention, still it will be understood that I do not limit myself to the exact details as set forth, excepting as come within the purview of the ensuing claims and a reasonable construction of the scope thereof contemplating 35 a fair range of equivalents.

What I do claim, as new and patentable, is:—

1. In dry closet fixtures, the combination 40 of a container receptacle having a hollow lateral extension leading peripherally from the interior thereof and closed at its outer end; an outlet apertured recessed seat formed on the underneath wall of said hollow extension; a support providing a vent 45 chamber having a lateral upturned elbow leading therefrom; means adapted to be snugly seated, in readily separable relation, within said apertured recessed seat and providing an exteriorly air-sealed communicat- 50 ing passage between said hollow extension and said upturned elbow, when said receptacle is positioned in operative relation therewith; and a vent pipe in communication with said vent chamber, substantially as de- 55 scribed.

2. In dry closet fixtures, the combination 60 of a container receptacle having a hollow lateral extension leading peripherally from the interior thereof and closed at its outer end; an outlet apertured recessed seat formed on the underneath wall of said hollow exten- 65 sion; a support providing a vent chamber having a lateral upturned elbow leading therefrom; tubular means forming a contin-

uation of said upturned elbow and adapted 65 to be snugly seated, in readily separable relation, within said outlet recessed seat; a sealing gasket interposed between the upper end of said tubular means and said recessed seat, the whole providing an exteriorly 70 sealed communicating passage between said hollow extension and said upturned elbow, when said receptacle is positioned in operative relation therewith; and a vent pipe in communication with said vent chamber, sub- 75 stantially as described.

3. In dry closet fixtures, the combination 80 of a container receptacle having a hollow lateral extension leading peripherally from the interior thereof and closed at its outer 85 end; an outlet apertured recessed seat formed on the underneath wall of said hollow extension; a support providing a vent chamber adapted to communicate with the exterior atmosphere and having a lateral 90 upturned elbow leading therefrom; and a retractile equalizing tubular element, adapted to be seated at its upper end within said outlet recessed seat, when said receptacle is positioned in operative relation therewith, 95 and at its lower end communicatively connected with said upturned elbow, the whole providing an exteriorly air sealed self adjusting connection between said hollow extension and said upturned elbow, substantially as described.

4. In dry closet fixtures, the combination 100 of a container receptacle having a vent conduit leading peripherally therefrom and closed at its outer end; an outlet apertured 105 recessed seat formed on the underneath portion of said vent conduit; a support providing a vent chamber adapted to communicate with the exterior atmosphere and having a lateral upturned elbow leading therefrom; a 110 guiding sleeve providing a continuation of said upturned elbow; and a spring controlled retractile tubular element slidingly mounted within said sleeve and adapted at its upper end to be snugly seated, in readily 115 separable relation, within said outlet recessed seat, when said receptacle is operatively positioned, the whole providing an exteriorly air sealed self adjusting connection between said receptacle vent conduit 120 and said upturned elbow, substantially as described.

5. In dry closet fixtures, the combination of 125 a container receptacle having a vent conduit leading peripherally therefrom and closed at its outer end; an outlet apertured recessed seat formed on the underneath portion of said vent conduit; a support providing a vent chamber adapted to communicate with the exterior atmosphere and having a lateral upturned elbow leading therefrom; a guiding sleeve providing a continuation of said upturned elbow; a spring controlled re-

4
tractile tubular element slidably mounted within said sleeve and adapted at its upper end to be snugly seated, in readily separable relation, within said outlet recessed seat, 5 when said receptacle is operatively positioned; and a sealing gasket carried by the upper end of said retractile element, the

whole providing an exteriorly air sealed self adjusting connection between said receptacle vent conduit and said upturned elbow, 10 substantially as described.

In testimony whereof, I affix my signature.
